UNITED STATES PATENT OFFICE.

WALTER BRUCE WILLS, OF BALTIMORE, MARYLAND.

COLLAPSIBLE BAG HOLDER.

1,424,387.

Specification of Letters Patent. Patented Aug. 1, 1922.

Application filed March 21, 1922. Serial No. 545,447.

To all whom it may concern:

Be it known that I, WALTER BRUCE WILLS, a citizen of the United States, residing at Baltimore city, State of Maryland, have 5 invented certain new and useful Improvements in Collapsible Bag Holders, of which the following is a specification.

This invention relates to devices for holding bags, and more particularly bags used 10 as strainers in the process of making jelly. It will be understood however that the device may also be used for holding various other kinds of bags and similar articles.

The invention has for its object to provide 15 a novel and improved holder of the kind stated which is foldable into small and compact form for convenience in shipment and storage.

With the object stated in view, the invention 20 consists in a combination and arrangement of parts to be hereinafter described and claimed, and in order that the same may be better understood, reference is had to the accompanying drawings, wherein,

25 Figure 1 is a side elevation of the device; Fig. 2 is a plan view thereof; Fig. 3 is a side elevation of a fragment of the device showing a modification; Fig. 4 is a plan view of the modified structure, and Fig. 5 is a 30 side elevation of the device showing the same partly folded.

Referring specifically to the drawings, the device consists, broadly speaking, of a base, a pivotally supported bag holder and a 35 means by which the holder is maintained in operative position.

The base member consists of a rectangular or otherwise shaped frame made up of a marginal wire 10 and cross wires 11, two of 40 which latter project outwardly from one end of the frame and are formed at their extremities into eyes 12 for pivotally supporting a standard which carries the bag holding member. The wires 11 may be welded or 45 otherwise rigidly secured to the marginal wire 10.

Near one end 13 of the base marginal wire 10 hereinbefore described from which two of the cross wires 11 project is pivotally 50 supported a prop for holding the bag-holder supporting standard in upright position, and the bag holder in operative position. This prop is composed of a pair of laterally spaced and parallel rods 14 having one end 55 fashioned into eyes 15 through which the bar 13 loosely passes, and having at their other

ends forward bends 16 connected at their extremities by a cross bend 17. The bends 16 are formed at their outer ends with depressions 18, and intermediate its ends the 60 bend 17 has a depression 19. The entire prop may be made of a single piece of wire bent into the shape shown and described.

The supporting standard of the bag-holder consists of a pair of laterally spaced 65 and parallel rods 20 connected at one end by a cross bar 21 which passes loosely through the eyes 12, whereby the pivotal support for the standard is had. The other ends of the rods 20 are connected by a cross 70 bar 22. The entire standard may be constructed of a single piece of wire bent to form the side portions 20 and the connecting end portions 21 and 22.

The bag-holding or supporting member 75 is also a single piece of wire bent into a ring 23, with two ends of the wire brought together, as shown at 24, and extending radially outward from the ring, and then bent laterally as shown at 25, and finally rear- 80 wardly as shown at 26, and formed with terminal eyes 27 through which the cross bar 22 loosely passes to provide a pivotal support for the ring 23. The bends 24 are secured together in any suitable manner such 85 as by a sleeve 28 as shown, but they may also be soldered or welded together and the sleeve dispensed with, whichever may be found the most desirable from a manufacturing standpoint. The bag-supporting ring 90 23 is therefore formed with a shank composed of a forward portion consisting of the bends 24, and a rear portion consisting of the laterally spaced members 26 connected to the bends 24 by the laterally and 95 inwardly extending bends 25.

The device is set up ready for use by swinging the standard and the prop to upright positions in such a manner that the cross bar 22 of the standard side rods 20 100 seats beneath the forward bends 16 of the prop side rods 14 and in front of said rods. The distance between the rear side portions 26 of the shank carrying the ring 23 is greater than the distance between the bends 105 16, and hence the parts 26 seat alongside the bends 16 on the outside thereof when the ring shank is swung down to place the ring in horizontal position, this being the bag-holding position. When the ring is in this 110 position, the bends 25 of the ring shank are behind the cross bend 17 of the prop, and

their outer ends seat in depressions 18, whereas the forward portion of the ring shank consisting of the parts 24 and 28, seat in the depression 19 of the cross bend 17. 5 This engagement of the ring shank with the depressions limits the downward swing of said shank, and the ring 23 is thus securely held in horizontal position. The prop and the standard converge toward their upper 10 ends when they are swung to upright position as described, and the interlocking engagement of the ring shank with the prop as hereinbefore described locks the prop and the standard together so that their upright 15 position is securely maintained.

To fold the device for convenience in shipment and storage, it is necessary only to disconnect the ring shank from the prop, which permits the prop and the standard to 20 be swung down to lie in horizontal position close to the base, the ring and its shank being swung down and come alongside the standard.

Figs. 3 and 4 show a slightly modified 25 structure. Here the side rods 14 of the prop have their forward bends 16 and the connecting cross bend 17 made straight, and to the cross bend is welded or otherwise rigidly secured a piece of wire 29 having 30 upturned end portions 30 behind which the lateral bends 25 of the ring shank seat when the device is set up. The parts 30 therefore prevent collapse of the standard and the prop in the same manner as the depressions 35 18 in the first described structure. In both structures the standard and the prop are securely locked together, and the ring is firmly held in operative position. The standard and the prop cannot be folded as 40 described until the ring shank is swung upwardly to clear the portions of the prop at the top thereof with which it is in engagement.

Both forms of the device are simple, 45 strong and durable in construction, effective

for the purpose intended and may be easily and cheaply manufactured.

I claim:

1. A bag-holder comprising a base, a standard composed of a pair of laterally spaced side rods connected by a cross bar at one end and having their other ends pivotally connected to the base, a bag-supporting member having a shank consisting of a forward portion carrying the member and a rear portion consisting of laterally spaced side members having inward bends at their forward ends whereby they are connected to the forward portion of the shank, said side members being pivotally supported by the aforesaid cross bar, and a prop consisting of laterally spaced side rods pivotally connected at one end to the base and having their other ends connected by a cross bar on which the aforesaid forward portion of the shank is adapted to seat to maintain the operative position of the said prop having portions thereof near its ends engageable by the aforesaid inward bends of the shank for maintaining the upright position of the standard and the prop. 50 55 60 65 70

2. A bag-holder comprising a base, a standard pivotally connected at one end to the base and having at its other end a cross bar, a bag-supporting member having a shank which is pivotally supported by the aforesaid cross bar, said shank having laterally directed portions intermediate its ends, and a prop pivotally connected to the base at one end and having at its other end 75 80 85 a cross bar on which the aforesaid shank is adapted to seat to maintain the operative position of the bag-supporting member, said prop also having end portions engageable by the aforesaid laterally directed portions of the shank for maintaining the upright position of the standard and the prop.

In testimony whereof I affix my signature.

WALTER BRUCE WILLS.
